UNITED STATES PATENT OFFICE.

JAMES N. STEVENSON, OF SALVISA, KENTUCKY.

DESIGN FOR A REIN-HOLDER.

SPECIFICATION forming part of Design No. 15,595, dated December 2, 1884.

Application filed July 29, 1884. Term of patent 14 years.

To all whom it may concern:

Be it known that I, JAMES N. STEVENSON, a citizen of the United States, residing at Salvisa, in the county of Mercer and State of Kentucky, have invented and produced a new and original Design for Rein-Holders, of which the following is a specification, reference being had to the accompanying drawing, forming a part thereof, in which a side view of my newly-designed rein-holder is shown.

My design consists of a rein-holder having the appearance of a duck's head with an elongated bill. A is the head of a duck, B a portion of the neck, and b b two halves of the bill, and c one of the eyes. The bill is elongated, and the upper half is tapering, and rounding on its upper edge and straight on

its lower edge, while the lower half is straight on its upper edge and tapering and rounding on its lower edge. 20

What I claim is—

The herein-described design for a rein-holder, consisting of a holder having the appearance of a duck's head with an elongated bill, the upper half of the bill being tapering, and rounding on its upper edge and straight on its lower edge, and the lower half straight on its upper edge and tapering and rounding on its lower edge, as shown. 25

JAMES N. STEVENSON.
